UNITED STATES PATENT OFFICE.

HENRY J. S. HALL, OF NEW YORK, N. Y.

SCREW-CAP CLOSURE.

SPECIFICATION forming part of Letters Patent No. 707,320, dated August 19, 1902.

Application filed February 12, 1902. Serial No. 93,740. (No model.)

To all whom it may concern:

Be it known that I, HENRY J. S. HALL, a citizen of the United States of America, and a resident of New York city, in the State of New York, have invented a new and useful Improvement in Screw-Cap Closures, of which the following is a specification.

This invention relates primarily to the closures of original packages or receptacles for tooth-powder adapted for conveniently discharging the contents upon the tooth-brush and to be tightly reclosed, so as to be free from liability to the accidental escape of the powder in traveling-bags and the like. Another characteristic aimed at in such receptacles is that it is rendered impossible or difficult to refill them when the original contents are exhausted in order that the trademarks and other indicia of such original contents may not be misapplied.

The improved closure may be used for any box, bottle, or jar for powders, liquids, or semisolids. As regards construction it is of that type in which the closure is constructed on the principle of the "screw."

Heretofore the externally-applied screw-cap has not been utilized in powder-boxes, so far as I am aware, owing to the impracticability of employing gaskets in such small closures, the difficulty of otherwise rendering the cap powder-tight, and the greater difficulty of guarding against reuse without undue expense.

The objects of the present invention are to render an externally-applied screw-cap powder-tight and inseparable, to facilitate the discharge of the powder upon a tooth-brush by the location of the mouth at the front of the box, to provide at the same time for graduating the discharge with nicety, and to embody these advantages in a simple and inexpensive receptacle which can be economically given away with the contents by a manufacturer to promote the use of a given powder, liquid, or semisolid.

A sheet of drawings accompanies this specification as part thereof.

Figures 1 and 2 are front views showing an improved powder-box respectively closed and open. Fig. 3 represents a magnified longitudinal section on the line A B, Fig. 2. Fig.

4 represents a top view, partly in section, on the line C D, Fig. 3.

Like reference letters and numbers indicate like parts in all the figures.

The improved box is intended and adapted to consist, including its closure, of three parts—viz., a body 1, which may be of any suitable material, as sheet metal, paper, wood, or glass; a die-formed cover 2 of suitable sheet metal, as ductile tin-plate or brass, and a screw-cap 3, which may conveniently be of the same material as the cover 2.

The body 1 is provided in any approved way with the customary label *a*, indicating the front of the box, and is filled at a tooth-powder factory, for example.

The cover 2, carrying the cap 3, is then applied and by means of a depending marginal flange *b* or its equivalent is inseparably attached to the body 1. The other features of the cover 2 are a conical top *c*, against which the lower edge of the cap 3 closes powder-tight, as in Fig. 1; a screw-threaded nozzle *d*, a closed upper end *e*, an outlet *f* in the front of the nozzle, near its lower end, and a stop *g*, raised on the external surface of the nozzle at a convenient point above the plane of the outlet *f*.

The cap 3 is composed of screw-threaded side walls *h*, fitted to the nozzle *d*, a closed upper end *i*, a milled rim *j*, and a stop *k*. The latter is formed by bending inward a lip of the metal of the cap adjacent to a slit in its lower edge and coacts with the stop *g* when the box is fully opened, as in Figs. 2, 3, and 4, to prevent the accidental escape and loss of the cap.

It will be apparent that by simply turning the cap 3 between finger and thumb the outlet *f* may be opened to any desired extent with the greatest nicety of adjustment and that whether the outlet be partially or fully opened the discharge is always in one and the same direction, (indicated by the label *a*.) It will also be seen that the cap is rendered "inseparable" to as full an extent as may be required and that even if it be removed by lifting the stop *k* the closed upper end *e* of the nozzle *d* militates against fraudulently refilling the box to as full an extent as is practicable. In other words, the only way

the improved box can be refilled is through the contracted outlet *f*.

The stops *g* and *h* are shown at the front of the box for convenience. One or both of them may be located at the back, and this is preferable in the case of the stop *k*. A single turn of the screw-cap *3* may be rendered sufficient to fully open the outlet *f*. The term "conical" may include any suitable dome-shaped construction, and other like modifications will suggest themselves to those skilled in the art.

Having thus described said improvement, I claim as my invention and desire to patent 15 under this specification—

1. A closure formed by a screw-threaded nozzle constructed with an outlet in its front near its lower end and provided with a stop above the plane of said outlet, and an imperforate screw-cap having an inwardly-projecting stop to engage with said stop on the nozzle when the outlet is fully opened.

2. A closure formed by a screw-threaded nozzle constructed with an outlet in its front 25 near its lower end and provided with a stop above the plane of said outlet, and an imperforate screw-cap having an inwardly-projecting stop at its lower edge to engage with said stop on the nozzle when the outlet is fully opened.

3. A closure formed by a screw-threaded nozzle constructed with an outlet in its front near its lower end and provided with a stop

above the plane of said outlet, and an imperforate screw-cap having an inwardly-projecting stop integral with the body of the cap to engage with said stop on the nozzle when the outlet is fully opened. 35

4. The combination, in a powder-box, of a suitable body, a cover for the same having a conical top and a screw-threaded nozzle having an outlet in its front near its lower end and provided with a stop on its outer surface above the plane of said outlet, and an imperforate screw-cap having its lower 40 edge provided with a stop to engage with said stop on the nozzle when the outlet is fully opened, and adapted to close powder-tight against said conical top.

5. The combination, in a powder-box having a screw-cap closure, of a suitable body having its front designated, a cover, inseparably attached to said body, having a screw-threaded nozzle provided with a closed upper end and an outlet in its front near its lower 50 end, and a screw-cap inclosing said closed upper end; said nozzle and said cap being provided respectively with stops arranged to engage each other when the outlet is fully opened and to prevent the removal of the cap, substantially as hereinbefore specified. 55
